UNITED STATES PATENT OFFICE.

EMIL KUHN-FREI, OF ZURICH, SWITZERLAND.

ELECTRIC POCKET-LAMP.

1,285,243.

Specification of Letters Patent. Patented Nov. 19, 1918.

Application filed April 7, 1916. Serial No. 89,663.

To all whom it may concern:

Be it known that I, EMIL KUHN-FREI, a citizen of the Swiss Confederation, residing at Neumühlequai No. 8, Zurich, Switzerland, 5 have invented new and useful Improvements in Electric Pocket-Lamps, of which the following is a specification.

The present invention relates to a new and improved electric pocket lamp.

10 One object of the invention is to provide a pocket lamp having no galvanic battery on replacing the same by a dynamo driven by a spring.

15 A further object of the invention is to provide a device for tensioning the spring while the lamp is used.

The present invention comprises other features which will appear in the course of the subjoined description.

20 Reference is to be had to the accompanying drawings forming part of this specification, in which similar characters of reference indicate corresponding parts in all the figures.

25 Figure 1 is a side section on line A—B of Fig. 2 showing the interior of the pocket lamp.

Fig. 2 is a section on line C—D of Fig. 1.

30 Fig. 3 is a top view of the lamp shown in Fig. 1.

In the drawings 1 represents a casing of sheet metal. A side 2 of the casing 1 is hinged to the casing 1 by means of a pin 3 fixed in the front wall 7 and in the back wall 35 8 of the casing 1. On the pin 3 there is a coiled spring 4 one end of which is fixed to the pin 3 the other end rests on the wall 2. The spring 4 tends to hold the wall 3 in the position shown in Fig. 1. On the wall 2 a 40 pawl 5 is linked at 6 which pawl engages a ratchet wheel 9 fixed on an arbor 10. The arbor 10 is rotatably mounted in the walls 7, 8. On the arbor 10 the one end of a strong coiled blade spring (not shown) is fixed the 45 other end of which is fastened to a barrel 11 which is provided with a toothed rim 12. The rim 12 is in mesh with a toothed gear 13 journaled on the back wall 8. The gear 13 drives by means of a toothed gear 14 an 50 armature 15 rotatably mounted in the walls 7 and 8. The armature 15 rotates between the poles 16, 17 of a magnet 18 arranged in the casing 1. On the armature there are two coils 19, 20 which are connected by insulated

wires to a lamp 21 mounted on the front wall 55 7 of the casing 1. On the back wall 8 of the casing 1 a retaining pawl 22 is arranged which engages the ratchet wheel 9, moreover there is fixed a pin 23 engaging a slot 24 in the side wall 2. Said slot 24 limits the 60 movement of the side wall 2. On the back wall 8 a disk 25 is rotatably mounted through which the one end of the arbor 10 projects. On the disk 25 an arm 26 is hinged which arm is bent-off at 27. The 65 free end of the arm 26 rests within a recess 28 arranged on the casing 1. The arm 26 is provided with a square hole 30 and the arbor 10 with a square head 32 which enters the hole 30 as soon as the arm 26 is brought in 70 the position shown in Fig. 2 in dotted lines. Arm 26 is used for turning the arbor 10 and tensioning the spring at the same time it serves for fixing the lamp on a wall, etc. One or more sets of gears may be arranged 75 between the barrel and the armature.

To make use of the lamp the spring is tensioned and the armature is set in rotation. The lamp is held in one hand and by pressing the side wall 2 and the casing against 80 each other the ratchet wheel is rotated and the spring re-tensioned.

Having thus described my invention I claim as new and desire to secure by Letters Patent:

85

1. A pocket lamp including a casing comprising front, rear, upper, lower and side walls, one of said side walls being hingedly secured at its upper end adjacent the upper wall of the casing, a current generator for 90 operating a lamp, a spring motor including a winding shaft for driving said generator, and means for keeping such spring motor constantly operating, such means including a pawl and ratchet mechanism, the ratchet 95 being mounted upon the winding shaft and the pawl having one of its ends pivoted to said hinged side wall, the other end engaging the said ratchet.

2. A pocket lamp including a casing comprising front, rear, upper, lower and side walls, one of said side walls being hingedly secured at its upper end adjacent to the upper wall of the casing, a current generator for operating a lamp, a spring motor for 100 driving said generator, means for keeping such spring motor constantly operating, such means including a pawl and ratchet 105

mechanism, the ratchet being mounted upon the winding shaft and the pawl having one of its ends pivoted to said hinged side wall, the other end engaging said ratchet, and re-
5 silent means engaging the hinged side wall for swinging the lower end thereof to its outermost position.

In testimony whereof I affix my signature in presence of two witnesses.

E. KUHN-FREI.
